[57] CLAIM

The ornamental design for a set of numeral-shaped pasta, as shown and described.

DESCRIPTION

FIG. 1 is a left-side elevational view of a set of numeral shaped pasta showing a first element of our new design; FIG. 2 is a top plan view thereof; FIG. 3 is a front elevational view thereof, the rear elevational view being a mirror image; FIG. 4 is a right-side elevational view thereof; FIG. 5 is a bottom plan view thereof; FIG. 6 is a top plan view of a set of numeral-shaped pasta showing a second element of our new design; FIG. 7 is a left-side elevational view thereof; FIG. 8 is a front elevational view thereof, the rear elevational view being a mirror image; FIG. 9 is a right-side elevational view thereof; FIG. 10 is a bottom plan view thereof; FIG. 11 is a top plan view of a set of numeral-shaped pasta showing a third element of our new design; FIG. 12 is a left-side elevational view thereof; FIG. 13 is a front elevational view thereof, the rear elevational view being a mirror image; FIG. 14 is a right-side elevational view thereof; FIG. 15 is a bottom plan view thereof; FIG. 16 is a top plan view of a set of numeral-shaped pasta showing a fourth element of our new design; FIG. 17 is a left-side elevational view thereof; FIG. 18 is a front elevational view thereof, the rear elevational view being a mirror image; FIG. 19 is a right-side elevational view thereof; FIG. 20 is a bottom plan view thereof; FIG. 21 is a top plan view of a set of numeral-shaped pasta showing a fifth element of our new design; FIG. 22 is a left-side elevational view thereof; FIG. 23 is a front elevational view thereof, the rear elevational view being a mirror image; FIG. 24 is a right-side elevational view thereof; FIG. 25 is a bottom plan view thereof; FIG. 26 is a top plan view of a set of numeral-shaped pasta showing a sixth element of our new design;

FIG. 27 is a left-side elevational view thereof;
FIG. 28 is a front elevational view thereof, the rear elevational view being a mirror image;
FIG. 29 is a right-side elevational view thereof;
FIG. 30 is a bottom plan view thereof;
FIG. 31 is a top plan view of a set of numeral-shaped pasta showing a seventh element of our new design;
FIG. 32 is a left-side elevational view thereof;
FIG. 33 is a front elevational view thereof, the rear elevational view being a mirror image;
FIG. 34 is a right-side elevational view thereof;

FIG. 35 is a bottom plan view thereof;
FIG. 36 is a top plan view of a set of numeral-shaped pasta showing an eighth element of our new design;
FIG. 37 is a left-side elevational view thereof;
FIG. 38 is a front elevational view thereof, the rear elevational view being a mirror image;
FIG. 39 is a right-side elevational view thereof; and,
FIG. 40 is a bottom plan view thereof.
